UNITED STATES PATENT OFFICE.

PETER J. WEIRICH, OF ADAMS, WISCONSIN.

LOCOMOTIVE FIRE DOOR.

Application filed May 12, 1921. Serial No. 468,826.

This invention relates to improvements in apparatus for opening and closing fire doors on locomotives or the like.

One of the objects of the invention is to provide apparatus of simple and strong construction which will reliably open and close the fire door quickly by manipulating a suitable control element which may be located in any convenient place.

10 A further object of the invention is to provide pneumatically operated means for opening and closing the fire door.

The invention contemplates the provision of a cylinder having a reciprocating piston which is operatively connected to the fire door in combination with means permitting the admission and discharge of air to and from the cylinder; and a further object of the invention is to provide means whereby 20 the air on the working side of the piston may be rapidly discharged until the piston reaches nearly the end of its return stroke and then slowly discharged during the remainder of the stroke whereby the fire door 25 is quickly moved from open to nearly its closed position and then slowly moved into its closed position.

A further object of the invention is to provide for the admission of air on the upper 30 side of the piston to aid in movement of the piston on its return stroke.

A further object of the invention is to provide a fire door consisting of two relatively movable sections, which are preferably balanced with respect to each other.

A further object of the invention is to provide means whereby the door sections may be partially separated and closed so that the condition of the fire may be observed whenever desired.

40 A further object of the invention is to provide means for manually opening and closing the fire door in case the air supply should fail or the pneumatic operating mechanism should for any reason fail to function.

The invention consists in the novel constructions, arrangements and devices to be hereinafter described and claimed for carrying out the above stated objects and such 50 other objects as will appear from the following description of certain preferred embodiments illustrated in the accompanying drawings, wherein—

Fig. 1 is a front elevational view of apparatus embodying the principles of the invention;

Fig. 2 is a sectional view of the valve controlling the admission and discharge of air to and from the cylinder;

Fig. 3 is a sectional view taken on the line 3—3 of Fig. 1;

Fig. 4 is a sectional view of the cylinder and certain valves associated therewith;

Fig. 5 is a sectional view taken on the line 5—5 of Fig. 1;

Fig. 6 is an enlarged sectional view taken on the line 6—6 of Fig. 1;

Fig. 7 is a sectional view of the main valve controlling the supply of air;

Fig. 8 is a detail view of the piston and its connecting link when the latter is disconnected from the fire door;

Fig. 9 is a side elevational view on an enlarged scale of the pedal operated mechanism for manipulating the control valve;

Fig. 10 is a detail view showing the pedal directly connected to the fire door;

Fig. 11 is a front elevational view;

Fig. 12 is a side elevational view of a modified structure in which one pedal is employed for opening the fire door and another pedal is employed for closing the same; and

Figure 13 is a fragmentary vertical sectional view taken approximately on the plane indicated by the line 13—13 of Figure 1, looking toward the right.

Like character of reference designate like parts in the several views.

Referring first to Figs. 1 to 7, inclusive, it will be seen that the apparatus includes a supporting plate 15 provided with an opening 16 and which is adjustably secured to the fire box by bolts 17, the opening 16 being normally closed by a fire door, designated as a whole by the reference numeral 18, and preferably consisting of sections 18^a and 18^b which are pivotally mounted on the plate 15 by bolts 19^a and 19^b, respectively. The fire door sections are balanced with respect to each other and are adapted to co-operate with guide plates 20^a and 20^b, respectively, secured to the plate 15, the coengaging surfaces of which are such as to force the sections tightly against the plate 15 when they are in their closed position.

The fire door sections are opened and closed simultaneously and the mechanism for opening and closing them includes a bell crank 21 pivoted at 22 to the plate 15 which is operatively connected with the door section 18^b by a pair of links 23, see Fig. 3, and with the door section 18^a by a pair of

links 24, see Fig. 6. Secured to a pair of laterally extending lugs 25 formed on the plate 15 is a cylinder 26 provided with a reciprocating piston 27, the latter being connected by a link 28 to one arm of the bell crank 21 by a connecting pin 29, see Figs 4 and 6. The pin 29 is provided with a circumferentially extending groove 30 which is adapted to receive a U-shaped latch member 31 secured to one arm of the link 28. By this arrangement when the latch member 31 is removed from the groove 30, the pin 29 may readily be withdrawn and the link 28 disconnected from the bell crank.

The piston in the cylinder is preferably moved by compressed air supplied by a pipe 32 leading from any suitable source of supply, for example, from the air reservoir of the air brake system (not shown), admission of air being controlled by a three-positioned main valve 33, see Fig. 7. A pipe 34 leads from the port 35 of the valve 33 into a port 36 formed in the cylinder 26 on the upper side of the piston. A pipe 37 leads from a port 38 of the valve 33 into a port 39 of a control element 40, see Fig. 2. The control element 40 is provided with an outlet port 41 which is adapted to receive one end of a pipe 42 the other end of which is formed so as to provide branch pipes 43 and 44 which lead into suitable ports 45 and 46, respectively, formed in the lower portion of the cylinder 26, see Fig. 4. Communication between the ports 39 and 41 of the control element 40 is normally shut off by a valve 47 held against its seat by a spring 48. The valve 47 is provided with a stem 49 formed with a circumferential groove 50 so that when the valve is in the position shown in Fig. 2, air from the pipe 42 may discharge into the controlling element 40 and pass to the atmosphere through a port 51. In the branch pipe 43 is provided a check valve 52 which permits inflow of air to the cylinder and in the branch pipe 44 is provided a check valve 53 which permits outflow of air from the cylinder. A restricted air outlet port 54 controlled by a needle valve 55 is provided in the check valve 52.

The control element 40 is preferably operated by means of a foot pedal 56, see particularly Fig. 9. The casing of the control element is provided with a pair of forwardly projecting lugs 57 between which is pivotally mounted a lever 58, the parts being arranged so that the valve stem 49 bears against the upper side adjacent the rear end of said lever. The forward end of said lever is rigidly connected by an extensible link 59 with the pedal 56, the lower end of the link 59 being slotted at 60 to receive the pedal bar and is provided with a locking pin 61 adapted to be inserted in any of the notches 62 formed in the upper side of the pedal bar

thus providing for horizontal adjustment of the link 59 with respect to the pedal.

The stem of the valve 33 is normally in the position shown in Fig. 7 in which case air is admitted to the cylinder 26 above the piston 27 and also the pipe 37. When the pedal 56 is depressed, the valve 47 is raised from its seat which permits air to pass from the pipe 37 into the control element 40 and thence into the pipe 42. From the pipe 42 the air passes through branch pipe 43 into the bottom portion of the cylinder 26. The pressure of the air below the piston is substantially equal to that of the air above the piston, but because of the greater area of the piston engaged by the air on the lower side thereof, as against the area of the piston engaged by the air on the upper side thereof, the piston is rapidly forced upwardly against the pressure on the upper side. Movement of the piston upwardly results in the bell crank being partially rotated in a clockwise direction, consequently the fire door sections are moved into the position shown in dotted lines in Fig. 1. When pressure on the pedal 56 is removed the weight of the link 59 and the action of the spring 48 permits the valve 47 to seat very quickly thus cutting off communication between the ports 39 and 41 of the control element 40. The air in the cylinder below the piston is permitted to discharge rapidly through the branch pipe 44, the pipe 42, into the control element 40 and out through the port 51 until the piston reaches nearly the end of its return stroke and cuts off port 46. The remainder of air in the cylinder below the piston can then only discharge slowly through the restricted port 54 in the check valve 52. By the arrangement last described the bell crank is rotated in a counterclockwise direction and the fire door sections are substantially closed very rapidly and then moved into their extreme closed position slowly to avoid slamming the two sections together. Downward movement of the piston is also aided by the pressure of the air on the upper side thereof which accelerates closing of the door sections.

In order to observe the condition of the fire means is provided for slightly rocking the bell crank by hand. For this purpose a lever 63 is slidably and rockingly mounted on the bolt 22, see Figs. 1, 6, and 13, the lower end of the lever being adapted to enter into engagement with a stop 64 formed on the plate 20^b and the upper end of the lever, when pushed inwardly, being adapted to lie between a lug 65 formed on the bell crank, and one end of the link 23. It will thus be seen that when the lever 63 is moved in a clockwise direction, the fire door sections are opened and when moved in the opposite direction they are closed.

When the air supply fails, or the pneumat-

ically operating mechanism fails to function for any reason, means is provided for manually opening and closing the fire door sections. In that event the pin 29 connecting the piston link 28 with the bell crank is withdrawn, the piston link being turned, to one side out of the way, substantially at right angles, as shown in Fig. 8, it being held in that position by a lug 28^a formed thereon. The upper end of the pedal link 59 is connected by means of a suitable pin 66 with the fire door section 18^a, the pin 66 being adapted to enter a suitable recess 67 formed in said pedal link 59. It will be obvious that when the pedal 56 is depressed both door sections will be swung into open position. An auxiliary pedal 68 pivoted on a supporting bracket 69 is operatively connected with the lower end of the pedal link 59, see Figs. 11 and 12. When the pedal 56 is depressed and the door sections are opened the pedal 68 is raised. Depressing the pedal 68 reverses the position of the parts, that is to say, raises the pedal link 59 and causes the door sections to be moved to their closed position.

I claim:

1. Apparatus of the class described comprising a fire door consisting of a pair of relatively movable pivoted sections, a bell crank, links connecting said bell crank to the respective sections, a cylinder, a piston in said cylinder, a piston rod pivotally connected to said piston and readily detachably connected to said bell crank, said piston rod being arranged to be moved to a position at substantially right angles to the axis of said piston when disconnected from said bell crank, means for maintaining said piston rod in said position, means controlling admission of air to said cylinder, and means controlling discharge of air from said cylinder, said last mentioned means permitting rapid discharge of air from said cylinder during the initial period of discharge and slow dis-

charge of air from said cylinder during the final period of discharge for the purpose described.

2. Apparatus of the class described comprising a fire door consisting of a pair of relatively movable pivoted sections, a bell crank, links connecting said bell crank to the respective sections, a cylinder, a piston in said cylinder, a piston rod pivotally connected to said piston and readily detachably connected to said bell crank, said piston rod being provided with a lug adapted to engage a portion of said cylinder to maintain said rod in a substantially horizontal position when it is disconnected from said bell crank, an air inlet port leading into said cylinder below said piston, an air discharge port leading from said cylinder, said discharge port being closed before the piston reaches the end of its return stroke, and a restricted air discharge port associated with said inlet port for the purpose described.

3. An apparatus of the class described comprising a fire door consisting of a pair of relatively movable pivoted sections; a bell crank; a pivot pin for said bell crank; links connecting said bell crank to the respective sections; servo-motor mechanism connected to said bell crank for moving the same; means for controlling said servo-motor mechanism; a handle slidably and rockingly mounted on said pivot pin adapted to be moved toward and from said bell crank on said pin; means on said bell crank adapted to be engaged by said handle when moved toward said bell crank, whereby motion of said handle may be transmitted to said bell crank; and a stationary stop adapted to be engaged by said handle when it is moved from said bell crank, whereby said handle may be held stationary in such position.

In testimony whereof, I affix my signature.

PETER J. WEIRICH.
